Letters Patent No. 69,182, dated September 24, 1867.

IMPROVED BUCKLE.

The Schedule referred to in these Letters Patent and making part of the same.

TO ALL WHOM IT MAY CONCERN:

Be it known that I, EZRA COLE, of Fairfield, in the county of Lenawee, and State of Michigan, have invented a new and useful improvement in Buckles; and I do hereby declare that the following is a full, clear, and exact description thereof, which will enable others skilled in the art to make and use the same, reference being had to the accompanying drawings, forming part of this specification.

The present invention relates to a buckle more especially intended for use as a buckle for hame and tug-straps to harnesses, which buckle is constructed in a novel and peculiar manner, and in its construction is an improvement upon a buckle for a similar purpose embraced in an application bearing even date herewith. In the accompanying plate of drawings my improvement in buckles is illustrated—

Figure 1 being a plan or top view of the same, and

Figure 2 a longitudinal section taken in the plane of the line $z z$, fig. 1.

Similar letters of reference indicate like parts.

A in the drawings represents the frame to the buckle, which consists of a plate, B, having side loops C, and an end cross-bar or piece, D, under which the tug-strap is passed to and through the opening D², and from thence under the swivelled plate E to the part F of the buckle-frame to which the hame-strap is hung. This part F of the buckle consists of two side pieces, G, that are made of an angular or curved shape, and extended through slots or openings I in the plate at proper distances apart, where they hang or turn, as shown more particularly in fig. 2. J, a cross-piece to the sides G, and connecting their outer ends K, the plate E being hung between their outer ends L; with the tongue or pin M to such plate toward and in the plate B in position to engage with the holes of the tug-strap when any one is brought opposite to the same. To the cross-piece J the hame-strap is hung.

By my improved construction of the buckle the tension of the tug-strap not only draws down the plate B, but as it draws on the tongue the front side of the plate E is drawn down, consequently producing a double pinching of the strap.

I claim as new, and desire to secure by Letters Patent—

A buckle, consisting of the plate B and frame F, having swivelled tongue-plate E, when all constructed substantially as and for the purpose described.

EZRA COLE.
